(57) **CLAIM**

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in light-weight broken lines that form no part of the claimed design. Further, the light-weight broken lines immediately adjacent the solid line portions of the design form the boundary of the design, with those light-weight broken lines forming no part of the claimed design. The even length heavy-weight broken lines in the figures depict stitching, which forms no part of the claimed design.
